RAIL ANCHOR

Harold G. Warr, Park Ridge, Ill., assignor, by
mesne assignments, to Poor & Company, a cor-
poration of Delaware

Application May 16, 1936, Serial No. 80,047

5 Claims. (Cl. 238—330)

This invention relates to rail anchors for resis-
ting longitudinal movement of railroad rails and
more particularly to one piece anchor de-
vices comprising a hook shaped portion for grip-
ping the top and bottom surfaces of a rail base
5 at one side of the rail, an under rail body portion
which extends across beneath the rail base and
abuts against a vertical face of a cross tie and
means at the other end of the anchor for engag-
ing the other edge of the rail base.

It has been customary, heretofore, to make
anchor devices of the above character from steel
bars of uniform cross section so that when the
hook shaped portion of the anchor is driven onto
15 either of the base flanges of a rail one of the side
faces of the under rail body portion of the anchor
will have a flat bearing against a vertical face of
a cross tie. The major portion of the grip of
such anchors for resisting creeping movement
20 of the rail is obtained from the gripping action
exerted by the hook-shaped portion on the top
and bottom surfaces of the rail base when the
under rail body portion of the anchor is pressed
against the vertical face of the cross tie by the
25 forces which tend to move the rail longitudinally.
In order to provide rail gripping surfaces of suffi-
cient width to take advantage of the above grip-
ping action and at the same time avoid any ac-
tual canting of the hook portion of the anchor
30 about an axis transversely of the rail, such an-
chors have been made heretofore of steel bars
which approximate a one inch square in cross
section. Another purpose of using bars of such
cross section is that they provide the under rail
35 body portion of the anchor with a tie bearing face
of suitable area to minimize the tendency of such
anchor body to cut into the vertical face of the
cross tie.

A principal object of the present invention is
40 to provide a rail anchor of the above general
character which may be formed from a bar of
smaller cross section than has been used hereto-
fore for an anchor of similar size and at the same
time provide substantially the same rail grip-
45 ping and tie bearing effects, as above mentioned,
which have heretofore required the use of bars
of larger cross-section.

According to the present invention, the anchor
50 is made from a rectangular bar which, as viewed
in the drawing, has a depth or vertical dimen-
sion somewhat greater than its horizontal thick-
ness and, preferably, both end portions of the bar
55 are flattened to provide bearing surfaces sub-
stantially wider than the under rail body portion
of the anchor. One flattened end portion of the
bar provides a jaw for engaging the top surface
60 of the rail base and is so arranged relative to the
under rail body portion of the anchor that the
bearing surfaces for engaging the top and bot-
tom of the rail base will have the same effective

width, for resisting the forces tending to rock
the hook portion of the anchor about a horizon-
tal axis, as that of the anchor heretofore formed
from bars of substantially greater cross sectional
area. 5

Another and more specific object of the invention
is to provide a rail anchor having a locking
shoulder at one end and having a flattened por-
tion at the other end to provide a gripping jaw
of greater width than the intermediate portion 10
of the anchor body, whereby the anchor can be
made of relatively light stock and at the same
time provide a relatively wide rail gripping sur-
face which cooperates with a portion of the an-
chor of narrower width to resist the forces tend-
ing to turn the anchor about a horizontal axis
and which cooperates with the locking shoulder
and with a stop surface at the jaw end of the
anchor to resist the forces tending to move the
anchor about a vertical axis to a diagonal posi-
15 tion on the rail, for example, when the adjacent
cross tie is shifted in the ballast of the roadbed
so as to engage but one end only of the anchor
body. 20

The invention is illustrated in the accompany-
ing drawing, wherein 25

Fig. 1 is a side view of a rail anchor device con-
structed in accordance with this invention.

Fig. 2 is a plan view of the rail and anchor de-
vice applied thereto, as shown in Fig. 1, and 30

Fig. 3 is a cross-sectional view taken on line
3—3 of Fig. 1 so as to illustrate the effective width
35 of the rail gripping surfaces for resisting the
forces tending to turn the jaws about a horizon-
tal axis when the body portion of the anchor is
pressed against a vertical face of a cross tie.

Referring to the drawing, 10 designates the
base portion of a railroad rail, 11 a supporting
cross tie, 12 a tie plate interposed between the
tie and the rail base, and 13 designates a rail
anchor made in accordance with this invention
40 and applied to the rail base. The anchor device
13, insofar as its general contour is concerned, is
of well known form and in this respect may be
briefly described as comprising a downwardly
45 bowed body or under rail portion 14. A hooked
end portion 15 at one end of the body provides
upper and lower jaws 16 and 17 for engagement
with one flange of the rail base 10. The said
jaws are formed so that they will be spread
50 apart slightly when they are driven onto the said
base flange and consequently exert a strong
spring grip on the top and bottom surfaces of
the rail base at one side of the rail. The rail
engaging surface 18 of the lower jaw bears
55 against the bottom surface of the rail base at a
location nearer the edge of the rail than the rail
engaging surface 19 of the upper jaw. It will
be seen, therefore, that by reason of the arrange-
ment of the above surfaces 18—19 at different
60

distances from the edge of the rail, the anchor will turn about an axis extending lengthwise of the rail when the jaws 16-17 are driven upon the wedge-like base flange of the rail and thereby force the bearing surface 20 at the other end of the anchor, against the bottom surface of the rail. A locking shoulder 21 engages the vertical edge portion of the rail adjacent the bearing surface 20 to hold the anchor in its applied position on the rail.

The general constructions described above are recognized as being old in the art. It is to be understood, therefore, that the present invention resides in the herein disclosed improvements which make it practicable to form an anchor of the above general character from a metal bar of relatively light cross section and at the same time provide a widened rail gripping surface at the jaw end of the anchor and preferably also at the locking shoulder end thereof which gives the improved anchor rail gripping portions having substantially the same gripping coaction as is obtained when such anchor is made from bars of heavier cross section.

According to the present invention an anchor of the above or similar configuration is made from a steel bar, the horizontal thickness of which is substantially less than the breadth or vertical dimension of the bar. Preferably one or both ends of the bar are flattened before the bar is bent to the configuration shown in Fig. 1. The flattened portion at one end of the bar provides the jaw 16 with a rail bearing surface 19 which is substantially wider than the bottom bearing 18 of the lower jaw 17. By inspection of Fig. 3 of the drawing it will be seen that the bearing surface 18 of the lower jaw 17 is centralized with relation to the width of the flattened portion or rail engaging surface 19 of the upper jaw. The overhang of the flattened upper jaw portion with relation to the opposite vertical faces of the under rail body portion permits the anchor to be driven onto the rail base at either side of the rail without interfering with the flat bearing of the under rail body portion against an adjacent cross tie. Either side of the under rail body portion of the anchor may bear against a vertical face of the cross tie, depending upon which side of the rail the anchor jaws engage. When the anchor is applied to a rail base and bears against a cross tie, in the manner indicated in Figs. 1, 2 and 3, the effective width of the upper and lower jaws for effecting the turning or shackle grip on the top and bottom surfaces, is the dimension indicated by the letter A. This dimension is preferably the same as is maintained in the anchors of the same general contour which have been made heretofore from bars of heavier cross section and provides for a strong grip on the rail base without any actual canting of the jaws and, therefore, without danger of spreading apart or opening of the jaws.

Inasmuch as a principal grip of anchors of the above character for resisting lengthwise movement of the rail is obtained by the grip of the hook shaped jaw portion on the top and bottom surfaces of one base flange of the rail, when the anchor body is pressed against a cross tie, it is important that the effective width of the jaw portion be sufficiently narrow to prevent it from sliding lengthwise of the rail when the anchor body is pressed against a cross tie and which, at the same time, will permit a strong gripping action at the edges 23-24 of the jaws without involving any actual canting of the jaws about a horizon-

tal axis. The flattened end portion of the jaw 16 is preferably curved, as indicated at 25. This curvature may be formed during the shearing of the bar or during the flattening of the end portions thereof. The bend 15 is preferably so formed as to contact the lower corner 26 of the rail base when the anchor is driven to the full limits of its applying movement. The said bend, therefore, provides a stop surface which prevents over-driving of the anchor during its application to the rail and limits movement of the hook end of the anchor transversely of the rail when the anchor is subjected to forces tending to turn the anchor about a vertical axis to a diagonal position on the rail base. The said upturned lug 21 and the surface 20 adjacent thereto, preferably, correspond in width to the flattened portion of the jaw 16 and therefore is substantially wider than the horizontal dimension of the downwardly bowed under rail portion of 20 the anchor. By widening the lug portion 21 by flattening the end of the bar so as to maintain the narrower portion of the bar centralized with relation to the lug 21, the anchor body is given an effective width, insofar as the engagement 25 with the opposite edges of the rail base is concerned, equal to the dimension indicated by the letter B. The engagement of the anchor with the rail at points indicated 27 and 28 cooperate to provide the anchor with a width sufficient to 30 resist the pressures ordinarily encountered in service tending to turn the anchor about a vertical axis to an abnormal diagonal position across the rail. The engagement of the anchor at the points 29 and 30 provide a corresponding resistance to forces tending to displace or shift the anchor about a vertical axis in the opposite direction. These forces are resisted also by an increased gripping action of the upper and lower jaws on the rail base flange produced by the turning movement of the widened upper jaw about a vertical axis passing through the point of engagement of the said stop surface with the edge of the rail base. The bearing 20 of the anchor being of greater width than the width of 40 the downwardly bowed portion of the bar is preferably so proportioned in length as to avoid contact with the cross tie.

While the invention has been illustrated and described in connection with certain specific construction, it should be understood that the invention is not restricted to the specific constructions shown and described except insofar as specific limitations appear in the appended claims.

I claim:

1. A light weight rail anchor comprising a bar having flattened and widened end portions which gradually increase in width and decrease in vertical thickness toward the ends and having an intermediate body portion of substantially rectangular cross-section having greater depth than its horizontal width, adapted to extend across beneath a rail with its wider faces arranged substantially perpendicular to the bottom of the rail base so that either wide face of the body may bear against a vertical face of a cross-tie, the said body portion of the bar being bent adjacent to one end into hook form to provide a wide upper jaw and a narrower lower jaw for gripping the top and bottom surfaces respectively of one base flange of the rail; the widened end of said jaw being of a width substantially corresponding to the depth of the said lower jaw which grips the bottom surface of the rail; and means comprising the flattened and widened portion at the other

end of the body for engaging a vertical surface of the other rail base flange to lock the anchor on the rail; the flattened portions of the bar, which form the said upper jaw and the said vertical surface engaging means, being positioned so that each flattened portion projects laterally beyond the tie engaging planes of the sides of the under-rail body portion of the anchor but only above the plane of the top of the cross-tie, whereby substantially the same effective rail gripping and tie bearing effects are produced as where said anchor is formed of uniform square cross-section, corresponding to the depth of the jaw which engages the bottom of said first mentioned rail flange, throughout the entire length of the anchor.

2. A light weight one-piece rail anchor comprising a bar having a flattened and widened end portion which gradually increases in width and decreases in vertical thickness toward the end of the bar and having a body portion which is of greater depth than its horizontal width adapted to extend across beneath the rail with its wider faces arranged perpendicular to the bottom of the rail base so that either wide face of the body may bear against a vertical face of a cross-tie, the said body portion of the bar being bent adjacent to said widened end into hook form to provide a wide upper jaw and a narrower lower jaw for gripping the top and bottom surfaces respectively of one base flange of the rail at different distances relative to the edge of the flange and having a stop surface for limiting movement of the hook transversely of the rail; and means for engaging a vertical surface of the other rail base flange to lock the anchor on the rail; the flattened portion of the bar which forms the said upper jaw being positioned so that it projects beyond the vertical tie engaging planes of the under-rail body portion of the anchor whereby the effective width of the anchor for resisting turning movement thereof about a horizontal axis is defined by the vertical plane of one side of the lower jaw and the edge portion of the widened upper jaw which projects beyond the plane of the other side of said lower jaw and whereby a turning movement of said widened jaw about a vertical axis passing through said stop surface increases the grip of the upper and lower jaws on the top and bottom surfaces of the rail base to resist such turning movement.

3. A one piece rail anchor comprising a bar having a flattened and widened end portion and having a body portion adapted to extend across beneath a rail with opposite faces arranged perpendicular to the bottom of the rail base so that either of said faces may bear against a vertical face of a cross-tie, the bar being bent adjacent to said widened end into hook form to provide a wide upper jaw and a narrower lower jaw for gripping the top and bottom surfaces, respectively, of one rail base flange at different distances relative to the edge of the flange and having a stop surface for limiting movement of the hook transversely of the rail; and means for engaging the vertical surface of the other base flange of the rail to lock the anchor on the rail; the flattened portion of the bar which forms the said upper jaw being positioned so that it projects beyond the tie engaging planes of the under-rail body portion of the anchor whereby the effective width of the anchor for resisting turning movement thereof about a horizontal axis is defined by the vertical plane of one side of the lower jaw and the edge

portion of the widened upper jaw which projects beyond the plane of the other side of said lower jaw and whereby a turning movement of said widened jaw about a vertical axis passing through said stop surface increases the grip of the upper and lower jaws on the top and bottom surfaces of the rail base to resist such turning movement.

4. A one-piece rail anchor comprising a bar having a flattened and widened end portion and having a body portion adapted to extend across beneath a rail with opposite faces arranged perpendicular to the bottom of the rail base so that either of said faces may bear against a vertical face of a cross-tie, the bar being bent adjacent to said widened end into hook form to provide a wide upper jaw and a narrower lower jaw for gripping the top and bottom surfaces, respectively, of one rail base flange at different distances relative to the edge of the flange and having a stop surface for limiting movement of the hook transversely of the rail; the flattened portion of the bar which forms the said upper jaw being positioned so that it projects beyond the tie engaging planes of the under-rail body portion of the anchor, whereby the effective width of the anchor for resisting turning movement thereof about a horizontal axis is defined by the vertical plane of one side of the lower jaw and the edge portion of the widened upper jaw which projects beyond the plane of the other side of the lower jaw; and means for engaging the vertical surface of the other base flange of the rail to lock the anchor on the rail and adapted to cooperate with the widened upper jaw and with the said stop surface of the hook to increase the grip on the rail during a turning movement of the anchor about a vertical axis passing through said stop surface.

5. A one-piece rail anchor comprising a bar having a flattened and widened end portion and having a body portion adapted to extend across beneath a rail with opposite faces arranged perpendicular to the bottom of the rail base so that either of said faces may bear against a vertical face of a cross-tie, the bar being bent adjacent to said widened end into hook form to provide a wide upper jaw and a narrowed lower jaw for gripping the top and bottom surfaces respectively of one rail base flange at different distances relative to the edge of the flange and having a stop surface for limiting movement of the hook transversely of the rail; the flattened portion of the bar which forms the said upper jaw being positioned so that it projects beyond the tie engaging planes of the under-rail body portion of the anchor, whereby the effective width of the anchor for resisting turning movement thereof about a horizontal axis is defined by the vertical plane of one side of the lower jaw and the edge portion of the widened upper jaw which projects beyond the plane of the other side of the lower jaw; and means for engaging a vertical surface of the other base flange of the rail to lock the anchor on the rail comprising a portion of the bar which decreases in thickness toward the end of the bar and is provided with a surface for locking engagement with the said vertical surface of the other base flange of the rail and thereby cooperates with the widened upper jaw and with said stop surface adjacent said jaw to increase the grip of the anchor on the rail during a turning movement of the anchor about a vertical axis passing through said stop surface.
